FIG. 1

FIG. 2

Product	Count of Opportunities	Sum of Amount	Count of Amount
this is test for very long text this is test for very long text t...
this is test for very long text this is test for very long text t...
this is test for very long text this is test for very long text t...
this is test for very long text this is test for very long text t...
this is test for very long text this is test for very long text t...
this is test for very long text this is test for very long text t...
this is test for very long text this is test for very long text t...
this is test for very long text this is test for very long text t...
this is test for very long text this is test for very long text t...

FIG. 3

FIG. 4